(57) **CLAIM**

The ornamental design for a chair arm, as shown and described.

DESCRIPTION

FIG. 1 is a perspective view showing the top, left side and front of a chair arm which forms my new design, the broken lines of a chair in this and other figures being for illustrative purposes only and forming no part of my design;
FIG. 2 is a right side elevational view thereof;
FIG. 3 is a left side elevational view thereof;
FIG. 4 is a rear elevational view thereof.
FIG. 5 is a top plan view thereof; and,
FIG. 6 is a front elevational view thereof.
The short, broken lines on the arm rest shown in FIGS. 1-6 are understood to represent stitching.
